UNITED STATES PATENT OFFICE.

WILLIAM H. BURSTALL, OF OXNARD, CALIFORNIA, ASSIGNOR TO DUNN MANUFACTURING COMPANY, OF OXNARD, CALIFORNIA, A CORPORATION OF CALIFORNIA.

WELL ELEVATOR.

Application filed February 16, 1921. Serial No. 445,530.

To all whom it may concern:

Be it known that I, WILLIAM H. BURSTALL, a citizen of the United States, residing at Oxnard, in the county of Ventura and State 5 of California, have invented new and useful Improvements in Well Elevators, of which the following is a specification.

This invention relates to well elevators, such as are employed for handling pipe, casing and other elements and parts used in drilling and operating oil wells or other deep wells. The invention has for its object to provide improvements in such well elevators, and particularly those which comprise 10 an elevator body and a gate hinged together and adapted to surround and embrace the work, the improvements pertaining particularly to the means for locking or holding the gate in closed position or closed with relation to the body, and for releasing such gate from such closed position so that it may be swung open to release or receive work. In accordance with the invention I provide a latch or bolt preferably upon the gate and 15 cooperating with the body, and means being provided for retracting such bolt from locked position, such latter means operating rotatably, so that it is turned to produce retractive movement of the bolt.

15 The invention has for further objects the provision of a well elevator which will be generally superior in efficiency and serviceability, taken in conjunction with relative simplicity and inexpensiveness of construction, and durability and compactness in 20 form and convenience in operation.

With the above and other objects in view, the invention consists in the novel and useful provision, formation, combination, construction, association and inter-relation of parts, members and features, all as herein-after described, shown in the drawing and finally pointed out in claims.

In the drawing:

45 Figure 1 is a perspective view of a well elevator embodying the invention;

Figure 2 is a perspective view of the closure or gate member of a well elevator embodying the invention;

50 Figure 3 is a cross sectional view of the gate shown in Figure 2, and taken on the line 3-3;

Figure 4 is a sectional view showing certain features of the invention;

Figure 5 is a cross-sectional view taken on 55 the line 5-5 of Figure 2;

Figure 6 is a perspective view of one of the latch members;

Figure 7 is a plan view of the latch member shown in Figure 6; and 60

Figure 8 is an end view of the latch member;

Figure 9 is a fragmentary cross-sectional view of means used between the suspension means and the holding means for maintaining the same in a predetermined relative position to the other; and 65

Fig. 10 is a front view of my invention.

Corresponding parts in all the figures are designated by the same reference characters. 70

Referring with particularity to the drawing, the well elevator comprises broadly, clamp and holding means A and suspension means B, therefor; the latter means being supported by hoisting means, not shown. 75 The clamping and holding means A includes two members a and b respectively. The member a may be designated the working body of the means A, and the member b may be designated the confining or closure body 80 or gate of the means A.

The bodies a and b are detachably united by connection means c which permit relative movement of the same; securing or latch means d being provided for maintaining 85 the members a and b in predetermined relative positions with relation to some load to be borne by the said members. The suspension means B which may be termed a bail, is joined with the member a, the weight of the 90 load being imposed upon said bail directly through the agency of said member a.

The member a comprises a substantially centrally bowed or curved portion 1 provided with oppositely extending trunnions 95 2 and 3. The member b consists of a bowed or curved portion 4 complementary to the bowed or curved portion 1 of the member a; whereby a substantially circular passage 100 when the closure member b is in connection with the member a, is formed. The bail B is provided with journal eyes on its ends for reception of the trunnions 2 and 3 of the member a, whereby the bail is journaled on the body of the elevator. The connection 105 means c and securing means d are applied to ends of the bowed or curved portions 1 and 4.

In Figure 1, in order to maintain the bail and the clamping and holding means A in a position as shown, means such as that illustrated in Figure 9 may be utilized.

5 Said means consists in forming a chamber u within the body member a. The journal eye on its inner face as at v where it coacts with the outer surface of the body member a is formed with a recess therein. A resiliently and outwardly urged ball member w may engage the recess v. The ball member w may be conveniently retained within the chamber u by downwardly striking the edge portion as x thereof so that the diameter formed is less than that of the diameter of ball member w. A spring member y may urge the ball outwardly as has been stated. Obviously, this particular arrangement overcomes the necessity of the operator holding the clamping and holding means in a position relative to that of the bail, as illustrated in Figure 1. Pressure exerted on an end of the means A will tend to release the ball member w from the socket v in the journal eye, so that the means A may assume another position with relation to the bail.

In the preferred construction in which the curved portions 1 and 4 unite in the formation of a circular passage, the portion 30 1 includes the major portion of such circular formation, being more than semi-circular, the portion 4 being consequently less than semicircular, and part of a total circular formation so constituted. The 35 common plane within which the trunnions 2 and 3 lie coincides substantially with the plane of the diameter of the circular passage included between the curved portions 1 and 4. The connection means 40 c and securing means d are arranged at one side of the plane last referred to, and in a plane coincident with the chord of an arc less than a semicircle in extension.

The connection means c comprises two 45 lugs 5 and 6 respectively, projecting from an end of the body b; combined with a lug 7 projecting from the body a substantially at the line of junction of the trunnion 3 and the central portion 1; and a headed pin or 50 pintle 8 passing through holes or openings 9 and 10 respectively, in the lugs 5 and 6 and a registering hole or opening in the lug 7. Two lugs 11 and 12 respectively project in spaced relation from the end of the curved 55 portion 4; and an outwardly projecting lug 13 is formed upon or connected with the body a and projecting therefrom substantially at the line of junction between the centrally curved portion 1 and the trunnion 2. 60 The latch means are adapted to operate between the lugs 11 and 12 and engage with the lug 13. The members just described, with the exception of the securing latch or latch means, are not features of the present 65 invention, the present invention residing in

the formation, arrangement and connection of the latch means and elements going to hold the closure member b in relation to the body member a.

The member b has formed on its outside 70 face 14 a member 15. The member 15 is provided with a circular recess 16 passing partly through said member and into the body member b. The body member b is provided with a longitudinal bore 17 communicating with the space confined between the lugs 11 and 12. Said bore 17 extends inwardly of the member b and has its passageway as at 18 in communication with the circular recess 16. As shown in Figure 3 80 where the bore 17 is in communication with the circular recess 16, the bore is not a complete circle. The inner periphery of the circular recess 16 is provided with an annular groove 19 and a perforation 20 produced 85 transversely through the member 15 communicating with said groove 19. The latch member b includes two parts, a bolt e and a turntable member f. The bolt e is elongated in formation, as shown at 21 and is confined 90 within the bore 17. The outer end of said bolt e as at 22 is curvally beveled. Said bolt member e is likewise provided with a vertical notched portion 23. A coil spring 25 within said bore 17 normally engages the 95 inner end 26 of the bolt and is confined between it and the end wall 27 of the bore 17, so that the bolt e is normally urged outwardly from the bore 17. The turntable member f comprises a circular body portion 100 28 provided at one face as at 29 with a flange 30, said flange being interrupted for a portion as at 31. An extension 32 formed with a transverse member 33 is joined to the flanged face 30 as at 34. The transverse 105 extension 33 constitutes handle means. The body portion 28 of the turntable member f is provided with an annular groove 35 located in its peripheral edge as at 36. Upon the other face 37 of the body 28 is placed a 110 lug 38, which is located near the peripheral edge of the body 28, as shown at 39. Referring to Figure 4 it is to be noted that the member f fits within the recess 16 of the member 15 and has the flanged portion 30 115 thereof engaging the surface 40 of the member 15. In said figure the annular groove 35 and the annular groove 19 are complementary to each other; also the lug 38 projects within the bore 17 located within the member b, and enters the slot 24 of said bolt. A rotation of the turntable member f will therefore cause the bolt e to be retracted within or extended from the bore 17. In the latter connection it is to be noted that the spring member 25 normally urges the bolt e from the bore 17, and in so urging causes rotation of the turntable member f. To limit the turning of the member f a projection 41 is formed on the face 40 of the member 15, as 120 125 130

at 42, and the interrupted portion 31 of the flange 30 engages opposite faces of the lug 41 and prevents the handle member from making a complete rotation. Thus if the 5 turntable member is within the recess 16, the bolt at all times is prevented from being displaced from the bore 17.

It is of course necessary to provide some means whereby the turntable member cannot 10 be taken from the recess 16, and to that end soft wire material is pushed upwardly through the perforation 20 so that it may pass into and extend within the annular grooves 19 and 35 and lock the turntable 15 member *f* to the member *b*. When the gate *b* is swung into a closed position with relation to the member *a* the curved nose 22 of the bolt *e* when it engages the lug 13 will tend to push back the bolt *e* within the bore 20 17 until such time as the nose comes into a notch 43 formed in the inner face of the lug 13. When this occurs the bolt will be limited 25 in its outward movement by the interrupted flange 30 of the turntable member *b*, co-operating with the projection 41.

It will thus be noted that a latch of this type provides a positive means whereby the gate of a well elevator may be quickly closed and quickly opened by an operator in a 30 minimum of time. At the present time it is necessary for a well operator when pulling a well elevator toward tubing, which tubing it is intended to lift, to hold on to the bail *B* and at the same time control the gate *b* of the means *A*. When the member *a* has its face 4 applied to a tube or the work to be 35 lifted, it is necessary for him to kick the gate *b* closed and operate the locking mechanism. This is an unhandy and difficult 40 feat, but with the mechanism just disclosed a kicking of the gate *b* will automatically lock said gate with relation to the member *a*. A simple rotation of the handle 33 will tend to retract the bolt *e* and allow the gate 45 *b* to again be opened.

It is obvious that the particular arrangement of the member *a* with relation to the closure member *b* permits the members *a* to carry the majority of the weight of the 50 work when the closure *b* is closed, although the lug 11 imposed part of the weight upon the lug 13.

I do not desire the invention to be understood as limited to the specific provision, 55 construction, formation and association of parts, members and features shown and described, but reserve the right to vary the same, in adapting the improvements to varying conditions of use, without departing 60 from the spirit of the invention and the terms of the following claims.

Having thus disclosed my invention, I claim:

1. The combination with a body and gate, 65 of a latch therefor, said latch comprising

a bolt and a turntable cooperating with the bolt to retract the same; said turntable having a handle, and its turning center being at one side of the path of play of the bolt; said turntable being provided with an interrupted flange, and the part of the gate upon which the turntable is mounted being provided with stop means cooperating with said interrupted flange to limit the turning movement of said turntable. 70

2. The combination with a body and gate, of a latch therefor, said latch comprising a bolt and a turntable cooperating with the bolt to retract the same; said gate being formed with a longitudinal bore therein, 80 and with a circular transverse recess on its outer face in communication with said longitudinal bore; said bolt being received within the longitudinal bore and said turntable being received within the transverse recess. 85

3. A body and gate provided with a latch, said latch comprising a bolt and turntable cooperating with the bolt to retract the same; said gate being formed with a longitudinal bore and with a circular transverse recess in communication with said longitudinal bore; said bolt being received within the longitudinal bore and the turntable being received in the transverse recess; said 90 turntable having its turning center at one side of the path of play of the bolt. 95

4. A body and gate having a latch, said latch comprising a bolt and a turntable co-operating with the bolt to retract the same; 100 said gate being formed with a longitudinal bore therein, and with a circular transverse recess in communication with said longitudinal bore; said bolt being received within the longitudinal bore and said turntable being received within the transverse recess; 105 said turntable including a curved body portion provided with an annular groove, there being a complementary annular groove within the transverse recess of the gate, and means adapted to be received between and within said annular grooves for maintaining the curved body portion of the turntable in the transverse recess of the gate. 110

5. A body and gate having a latch, said latch comprising a bolt and a turntable co-operating with the bolt to retract the same; 115 said gate being formed with a longitudinal bore therein, and with a circular transverse recess in communication with said longitudinal bore; said bolt being received within the longitudinal bore and said turntable being received within the transverse recess; 120 said turntable including a curved body portion provided with an annular groove, there being a complementary annular groove within the transverse recess of the gate, and means adapted to be received between and within said annular grooves for maintaining the curved body portion of the 125 gate. 130

4
turntable in the transverse recess of the gate; said bolt being formed with a vertical notch, and one face of the body being provided with a lug for reception in the vertical notch of the bolt, whereby a turning of the turntable will tend to extend or retract the bolt within the longitudinal bore of the gate.

6. A body and gate having a latch, said latch comprising a bolt and a turntable cooperating with the bolt to retract the same; said gate being formed with a longitudinal bore therein, and with a circular transverse recess in communication with said longitudinal bore; said bolt being received within the longitudinal bore and said turntable being received within the transverse recess; said turntable including a curved body portion provided with an annular groove, there being a complementary annular groove within the transverse recess of the gate, and means adapted to be received between and within said annular grooves for maintaining the curved body portion of the turntable in the transverse recess of the gate; said bolt being formed with a vertical notch, and one face of the body being provided with a lug for reception in the vertical notch of the bolt, where-

by a turning of the turntable will tend to extend or retract the bolt within the longitudinal bore of the gate; said turntable being provided with an interrupted flange, there being a projection upon said gate adapted to engage with said interrupted flange to limit the turning movement of the turntable.

7. A body and gate provided with a latch; said latch comprising a bolt, and a turntable cooperating with the bolt to retract the same; said gate being formed with a longitudinal bore and with a circular transverse recess in communication with said longitudinal bore; said bolt being received within the longitudinal bore and said turntable being received within the transverse recess; there being yielding means within the longitudinal bore normally engaging the inner end of the bolt for urging said bolt outwardly from said bore; the outer end of said bolt being curvedly beveled.

In testimony whereof, I have signed my name to this specification in the presence of two subscribing witnesses.

WILLIAM H. BURSTALL.
